UNITED STATES PATENT OFFICE.

JOHANN STUMPF, OF BERLIN, GERMANY.

OPERATING MECHANISM FOR INLET VALVES.

Application filed June 3, 1920, Serial No. 386,419, and in Germany December 18, 1914.

The invention relates to an inlet valve gear for steam engines, or engines using a primary medium having high initial pressure and subsequent expansive force and having a two cycle operation. The ordinary valve gears have the draw-back that the opening of the valve does not in the least follow the piston speed. If the governor has, for instance, set the eccentric to give 5 a cut-off from 8 to 10%, then an exceedingly small portion of the eccentric travel is active, giving extremely slow opening and closing of the valve and therefore excessive throttling of the steam, which condition naturally becomes worse for cut-offs smaller 15 than 8 to 10%. Furthermore the idle motion is large. Eccentric and inlet valves have to be of large dimensions, which increases the difficulties for the governor to act properly. 20 The large valves bring about increased leakage, large clearance volume and surface.

According to the present invention, the existing valve gears are to be improved by making the lay-shaft angular speed relative 25 to the engine speed, as for example a multiple of the crank shaft angular speed.

In accordance with the present invention means are provided to multiply the angle of the eccentric circle active for the motion 30 of the valve, which means a higher segment for this motion. With a lay-shaft angular speed for example of twice the crank shaft angular speed, it is possible to increase the valve lift about four times for 35 a cut-off of 10%. Accordingly, a valve of substantially less diameter than that of the one used with the ordinary valve motion would be sufficient. Clearance space, clearance volume, weight of valve and leakage 40 are reduced in an even higher ratio and the lay-shaft governor would appear to be four times as powerful.

Since the valve is to open but once for 45 every engine turn, this new valve motion makes the lay-shaft operative to actuate the valve once only for each revolution of the crank shaft.

One method, for instance, in case the lay-shaft angular speed is twice the engine 50 speed, is to arrange a second or auxiliary shaft preferably parallel to the lay-shaft and drive it at engine speed. This shaft acts upon the mechanism connecting eccentric and valve in such a manner as to

make it ineffective at every second revolution of the lay-shaft.

Or in some cases it would be advantageous to run the lay-shaft at engine speed, and the auxiliary shaft at twice engine speed.

Referring to the drawings, which illustrate merely by way of example, suitable means for the embodiment of my invention:—

Fig. 1 is a sectional view and partly diagrammatic showing an arrangement for effecting my invention, the valve being shown in closed position.

Fig. 1^a is a fragmentary detail on a reduced scale showing the position of the elements with the valve in the open position.

Fig. 1^b is a similar view showing another position of the elements with the valve closed.

Fig. 2 is a plan view in part section of same.

Figs. 3 to 8 inclusive, are diagrammatic views showing modifications.

Fig. 9 is a partial front view of a modification.

Fig. 10 is a plan view in part section showing same modification.

Fig. 11 is a diagram illustrating the old and new valve motion.

Fig. 12 is a plan view, on a reduced scale, of the engine showing the relation of the main or crank shaft with the lay shaft.

Similar reference letters refer to corresponding parts or elements throughout the several views.

Several different arrangements of this valve gear are shown in Figs. 1 to 10, while Fig. 11 in a diagrammatic way illustrates the old and the new valve movement. In all the examples shown, the lay-shaft has twice the angular speed of the crank shaft.

The first arrangement, as shown in Figs. 1, 2, and 12, has a shaft governor A mounted on the lay-shaft *a* which is driven at twice the angular speed of the crank shaft. Adjacent to this lay-shaft is placed another, or auxiliary shaft *b*, as shown in Fig. 2, driven from the lay-shaft by spur gears S with a ratio 1:2.

The eccentric on shaft *a* has the equivalent of a very short rod *c* upon the end of which acts eccentric *b'* of shaft *b* by means of rod *d*. Eccentric rod *c* is connected, by rod *c'*, to lever *f*, provided with a roller

on its free end for actuating the cam mechanism of the valve.

The action of rod d , derived from shaft b and eccentric b' is to move rods c and c' into and out of alinement, in a toggle joint like way, so that at every second revolution of the lay-shaft, roller lever f is not actuated to open the admission valve.

This will be evident when it is noted, in Fig. 1, that elements e and c of the eccentric on shaft a are approaching the nearest point to lever f and that c and c' are in alinement, because of the relative position of the eccentric b' . The completion of the movement which brings elements e , c and c' in alinement causes the actuation of lever f to open the inlet valve.

The short length of eccentric rod c further increases the valve lift with the same size eccentric and active angle.

Upon the next complete revolution of shaft a , the shaft b has only made a one-half revolution. The element or eccentric b' will have reached a point, as in Fig. 1^b substantially opposite that shown in Fig. 1. This will cause the movement of the point of connection of c and c' out of alinement so that at the end of this rotation of shaft a there will be no actuation of lever f .

Fig. 3 shows the bell crank lever f mounted upon a second lever f' of similar shape which is pivoted on the valve bonnet. Eccentric rod c acts immediately upon lever f while lever f' is connected by means of rod f^2 to eccentric shaft b .

The motion of lever f combines the motion of both shafts a and b according to the lever ratio with the result that also in this case the valve is opened once for each revolution of shaft b .

The arrangement shown in Fig. 4 has the eccentrics of shafts a and b connected to lever f by means of rods c and f^2 and a double lever g which is pivoted to arm f^4 of lever f .

The only difference between Fig. 4 and Fig. 5 is that in Fig. 5 the left end of double lever g is connected to lever f which is pivoted at f^3 and rod f^3 connects to the middle of lever g .

Fig. 6 shows the bell crank lever f carried on the single lever h . Eccentric rod c acts immediately upon lever f . Lever h receives its motion from shaft b by means of cam mechanism i . This cam is shaped in such a manner that during the period the valve is moved, pivot f' of lever f remains stationary.

Fig. 7 shows the valve operated by a walking lever f resting against single lever k which receives its motion from shaft b by a mechanism similar to the one employed in Fig. 6.

Fig. 8 employs a cam mechanism in which

the governor acts upon lever w the lower end of which has linked to it lever w' , which by means of eccentric rod w^2 is connected to shaft b . Eccentric strap e' of eccentric e on shaft a is, by means of rod c , linked to lever w' .

The purpose of shaft b in this case is to bring eccentric strap e' , at every second revolution of lay-shaft a , into a position corresponding to zero cut-off without interfering with the action of the governor.

Figs. 9 and 10 illustrate a partial front and plan view or section respectively, of a single eccentric valve gear. Eccentric e on shaft a , and under control of shaft governor g , oscillates shaft r by means of arm r' . Cam drum m and spur gear S' are loose on shaft r , but secured against relative lateral motion with respect to shaft r . In mesh with spur gear S' is another gear S^2 , the ratio being 1:2. Gear S^2 is keyed to shaft a .

The two inlet valves are operated by cams σ on shaft r . This shaft is moved longitudinally, the cams σ being placed in such manner that the valves are moved alternately. The mechanism for the longitudinal movement of shaft r consists of drum m having a suitable groove into which projects a fixed pin m' .

It is important to point out that this type of valve gear makes possible the use of single beat valves, which possess advantages over double beat valves.

Diagram Fig. 11 is illustrative of the operation in accordance with my invention and is based on eccentric speed twice the engine speed. The useful angle of the eccentric circle, normally α , is thereby doubled, as 2α , and increases four times the effective action of the eccentric rod as indicated by the distances 3 and 12.

If the lay shaft is arranged to run at double the engine speed, then the period of valve opening extends through twice the angle α and the width of the opening increases from A' to A , as shown in Fig. 11, since

$$A = r \cdot \sin \frac{2\alpha}{2},$$

therefore $A = 4 A'$, approximately within fairly wide limits.

In this formula, r represents the radius of the circle, and A the height of the segment which belongs to a sector of which α is half the center angle.

What I claim is:—

1. In operating mechanism for engine inlet valves, the combination with the engine crank shaft of a lay shaft operating at twice the number of revolutions as that of the crank shaft, and means for opening the valve, actuated by the lay shaft, to increase the speed of the valve opening relatively to the crank shaft speed and thereby propor-

tionally increase the extent of valve opening within a required period of each engine cycle, and means associated therewith to prevent the valve from being opened more than once for each revolution of the crank shaft.

2. In operating mechanism for engine inlet valves, the combination with the engine crank shaft of a lay shaft operating at a multiple of the revolutions of the crank shaft, and means for opening the valve, actu-

ated by the lay shaft, to increase the speed of the valve opening relatively to the crank shaft speed and thereby proportionally increase the extent of valve opening within a required period of each engine cycle, and means associated therewith to prevent the valve from being opened more than once for each revolution of the crank shaft. ¹⁵

JOHANN STUMPF.
